UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed December 14, 1927, Serial No. 239,861. Renewed February 24, 1930.

This invention relates to improvements in railway draft riggings.

One object of this invention is to provide a draft rigging for railway cars, including shock absorbing means so arranged and designed as to effectively take care of all shocks encountered in service, wherein the car is provided with center sills fixed thereto and having slidable draw sill members co-operating therewith, the slidable sill members functioning as a continuous drawbar, movement of the slidable sill members being resisted by the shock absorbing members which react between the fixed and draw sills and are arranged to distribute the applied forces at spaced zones throughout the length of the car, thereby reducing to a minimum the strain to which the center sills and the car structure is subjected and preventing damage to the same.

Another object of the invention is to provide a mechanism of the character indicated, including draft or center sills fixed to the car structure and movable draw sills, co-operating therewith, wherein relative movement of the sills is resisted by shock absorbing means reacting between the sills to absorb the lighter shocks with additional shock absorbing means reacting between the draw sills and the usual reacting between the draw sills and the usual drawbar members at opposite ends of the car to absorb the heavier shocks.

Still another object of the invention is to provide a railway draft rigging of the character indicated, including draw sill members which are movable bodily with respect to the car, the draw sill members being operatively connected to drawbars at opposite ends of the car, and cushioning means reacting between the car and the draw sills, wherein the cushioning means includes a plurality of elements arranged in spaced relation throughout the length of the car structure to distribute the applied forces, and friction shock absorbing means is provided, reacting between the drawbars and draw sills to absorb the heavier buffing shocks.

A further object of the invention is to provide a draft rigging for railway cars, including center sills fixed with respect to the

car structure and movable draw sill members telescoped therewith, the movable sill members functioning as a continuous drawbar, and cushioning means reacting between the movable and fixed center sills so arranged as to permit a relatively great amount of movement between the fixed and movable draw sills, whereby the shock absorbing capacity of the mechanism may be increased within wide limits, without effecting any material elongation of the train of cars in draft and any material shortening of the train in buff.

A more specific object of the invention is to provide a draft rigging for railway cars, including fixed center sills secured to the car structure, movable draw sills disposed between the fixed sills and extending substantially the entire length of the car, the fixed and movable draw sills being provided with housing sections co-operating to form spring pockets, springs disposed within the pockets between the end walls thereof for opposing movement of the draw sills with respect to the fixed sills, drawbar means at each end being anchored to the draw sills to permit relative movement between the parts during both buff and draft, shock absorbing means interposed between the drawbars and movable sills to oppose relative movement thereof, and means co-operating with the fixed and draw sills to limit the relative movement thereof.

Other and further objects of the invention will more clearly appear from the description and claims hereinafter following.

In the drawings forming a part of this specification, Figure 1 is a side elevational view, partly broken away, illustrating a railway draft rigging embodying my improvements. Figure 2 is a horizontal, longitudinal, sectional view of the front end portion of the structure illustrated in Figure 1. Figure 3 is a transverse, vertical, sectional view, corresponding substantially to the line 3-3 of Figure 2. Figure 4 is a vertical, transverse, sectional view, corresponding substantially to the line 4-4 of Figure 2. And Figure 5 is a side elevational view of a portion of one of the side sill members, illustrat-

ing the arrangement of the spring pockets.

In said drawings, 10—10 indicate the usual front and rear bolsters of a railway car, 11—11 designate the end sills of the car, 5 and 12 indicates the usual drawbar at one end of the car, it being understood that a similar drawbar is employed at the other end of the car structure.

My improved railway draft rigging comprises broadly, fixed center sill members A—A; slideable draw sill members B—B; draft key or follower bar members C—C, D—D, and E—E; front and rear combined yoke and friction shell members F—F; front 15 and rear follower blocks G—G; sectional spring pocket members H—H; spring resistance elements J—J; friction means K—K co-operating with each friction shell member; and spring resistance means L—L within each 20 friction shell member.

The draft sills A are of the usual form, being provided with top and bottom flanges 13—13, which extend outwardly. Both of the sills A are suitably secured to the car 25 underframe structure, including the bolsters 10 and the end sills 11, in any well known manner. Both of the sills A are provided with longitudinally disposed key receiving openings at the opposite ends thereof. As 30 shown in the drawings, two sets of openings are provided at each end of the sills A, the openings of one set being indicated by 14 and the openings of the other set being indicated by 15. The key receiving slots or openings 14 are of much greater length than the openings 15, as clearly illustrated in the drawings. The openings 14 and 15 are reinforced by cheek plates 16—16, suitably secured to the outer sides of the sills A. As shown, the 40 cheek plates are provided with flanges which extend into and reinforce the openings 14 and 15.

The movable sills B, which extend the entire length of the car structure, are of channel-shaped section, as most clearly illustrated in Figures 3 and 4. The top and bottom flange sections of the sills B are inwardly directed. Each of the sills B is provided with three key receiving openings at opposite ends thereof, the openings being designated by 17, 18 and 19, respectively. The openings 17 and 18 are reinforced by cheek plates 20, having flanges extending into said openings. The cheek plates 20 are secured 50 in any suitable manner to the sills B. The openings 19 are also reinforced by cheek plates 21, which are secured to the inner sides of the sills B and have reinforcing flanges extending into the openings 19. As most 55 clearly illustrated in Figures 2 and 3, the reinforcing flanges of the plates 21 extend entirely through the openings in the sills B and engage the inwardly extending reinforcing flanges of the cheek plates 16 on the sills 60 A. It will be evident that due to the flanges

of the plates 21 and the plates 16 engaging, the movement of the sills B will be accurately guided between the sills A.

The key or follower bar C extends through a transverse opening 22 in the drawbar, 70 snugly fitting the same, and has the opposite ends thereof projecting through the openings 14 and 17 of the sills A and B, respectively. It will be evident that the drawbar is thus mounted for limited movement with respect to the sills B in both directions. The filler block G is interposed between the inner end of the drawbar and the friction shock absorbing means K. The follower block G is provided with a transverse opening 23, in which the key or follower bar D snugly fits. The opposite ends of the key D extend through the openings 14 and 18 of the sills A and B. The openings 18 are of such a length as to permit limited inward movement of the key 80 D with respect to the sills B. The key or follower bar E is disposed in back of the combined friction shell and yoke member F and serves as an abutment means for the same. This key snugly fits the openings 19 90 of the sills B, so that the sills will be compelled to move in unison with said key. The outer ends of the key E extend through the openings 15 of the sills A, and the key is limited in its movement in both buff and draft 95 by engagement with the front and rear end walls of said openings. To prevent lateral displacement of the keys C, D and E, any suitable means may be employed. As indicated, cotter pins or similar members 24—24 100 are provided in the outer ends of the keys and co-operate with the cheek plates at the corresponding sides of the sills A. The combined yoke and friction shell F at each end of the mechanism comprises a main body member 105 25, forming the friction shell section proper. At opposite sides the friction shell section is provided with forwardly extending arms 26—26, embracing the inner end of the drawbar and the filler block G. The spaced arms 110 26 are each provided with two key receiving openings or slots 27 and 28, the key receiving slot 27 slidably accommodating the key C, and the slot 28 slidably accommodating the key D. At the rear end, the friction shell section is provided with top and bottom arms 29, which extend over and embrace the key E. 115 As will be evident, the arms 29 act as supporting means for the rear end of the combined yoke member and friction shell, and the keys C and D serve to support the front 120 end of said member.

The friction system which co-operates with the friction shell member comprises the usual friction shoes 30—30 and the co-operating wedge member 31. The wedge member 31 bears at its outer end directly on the inner side of the filler block G. The spring resistance means L is disposed within the friction shell member and has its opposite 130

ends bearing on the end wall of the shell and the inner ends of the friction shoes respectively. The parts of the friction shock absorbing mechanism are held assembled and of overall uniform length by the usual retainer bolt 32.

As most clearly illustrated in Figure 1, the sills A and B are provided with a plurality of spring pocket members H. As shown in said drawings, each pair of sills A and B is preferably provided with five of such pocket members. Each pocket member comprises two relatively movable sections, as most clearly illustrated in Figure 2. The pocket members are arranged in transversely aligned sets, and the inner sections of the pocket members of each set are formed by a casting 33, which is secured to the spaced sills B and forms a tie member between these sills. The outer section of each pocket member is formed by the casting 34, secured to the corresponding sill A. As most clearly illustrated in Figure 2, each casting 33 is provided with transversely extending, vertically disposed, tie walls 35-35, at the front and rear ends thereof. The tie walls 35 are connected at opposite sides by longitudinally extending spaced walls 36, which form the inner walls of the corresponding set of spring pockets. As most clearly illustrated in Figure 4, the walls 36 are curved to conform to the contour of the spring coils J. Each inner pocket section is also provided with front and rear end walls 37-37, which form continuations of the connecting walls 35 and serve as abutment means for the front and rear ends of the spring resistance elements J.

The outer sections of the pockets formed by the castings 34 are fixedly secured to center sills A. Each of the castings 34 is provided with front and rear flanges, as most clearly shown in Figures 2 and 4, which are secured to the sills A by rivets or other suitable means. Each casting A is provided with front and rear transverse walls 38-38, which serve as abutment means for the front and rear ends of the spring resistance J. The castings 34 are provided with side openings 39, through which the springs may be inserted within the pockets. The side opening of each casting is closed by a cover plate 40, which has a curved wall section corresponding in contour to the coils of the spring resistance J. The cover plate 40 is held in assembled position by a pair of longitudinally extending bolts 41-41, disposed at the top and bottom of said plates and extending through the end walls 38 of the casting 34. As will be clear upon reference to Figures 2 and 4, the end walls of the spring pockets are vertically divided at the center, the wall sections 37 being carried by the movable draw sills B and the wall sections 38 being carried by the fixed sills A. The spring resistance means J, disposed within each pocket, preferably comprises a light in-

ner coil and a relatively heavier outer coil, having their opposite ends bearing on the front and rear end walls formed by the wall sections 37 and 38.

It will be understood that the mechanism hereinbefore described is duplicated at opposite ends of the car, and that the parts at each end of the car function in a similar manner.

In the normal position of the parts, the follower key C is spaced at equal distance from the front and rear ends of the slots or openings 17 of the sills B, and engages the front end walls of the openings 27 in the side arms of the combined yoke member and friction shell F. The key D engages the front end walls of the openings 18 of the draft sills B, and also the front end walls of the openings 28 of the yoke arms. The rear edge of the key D is spaced from the rear end walls of the openings 18 and 28 a distance equal to the spacing between the rear edge of the key C and the rear end walls of the openings 17 and 27. The front edges of the keys C and E are preferably spaced equal distances from the front ends of the slots 14 and 15, respectively, of the sills. As will be evident upon consideration of the disclosure in the drawings, the movement permitted by the keys between the drawbar and the yoke and sills B is considerably less than the movement permitted between the keys and the fixed draft sills A. It will be appreciated that the relative proportions of the parts may be varied, so that the comparative movement of the parts may be varied within wide limits. The parts are preferably so proportioned that a movement of approximately two inches is permitted between the drawbar and the sills B, and a movement of approximately four inches is permitted between the draw sills B and the fixed sills A.

In the operation of my improved railway draft rigging, assuming a draft action being applied to the drawbar 12 at the left-hand end of Figure 2, the drawbar will be pulled outwardly, carrying the combined yoke and friction shell F forwardly therewith through the medium of the connecting key C. Movement of the wedge block at this time will be yieldingly resisted by the action of the springs J which oppose movement of the sills B-B, the wedge 31 being in engagement with the follower G which is connected to the sills B by the key D. As the combined yoke and friction shell is carried forwardly, the wedge 31 will exert a wedging action on the shoes, and the shoes and shell will move relatively to each other effecting compression of the spring resistance means L, at the same time the wedge will be carried forwardly carrying the filler block G and the key D therewith. The key D, which engages the front end walls of the openings 18 and the draft sills B, compels the latter to move forwardly also.

The entire movable sills B will thus be carried forwardly, compressing the spring resistance elements J disposed along the length of the sills A and B between the walls 5 37 at the one end of the spring pockets H and the walls 38 at the opposite ends of said pockets. Inasmuch as the walls 38 are fixed with reference to the sills A, the spring resistance elements J will cushion the shock 10 due to the draft action, and there will thus be a blending action of the friction and spring shock absorbing mechanisms. Compression of the friction shock absorbing mechanism will be limited by movement of the combined 15 yoke and friction shell F being limited with respect to the sills B—B through engagement of the inner end walls of the slots 28 with the key D. At the same time, movement of the key C, with respect to the sills B—B, 20 will be limited by engagement of this key with the front end walls of the slots 17—17. Movement of the sills B—B, with respect to the sills A—A, will be limited by engagement of the key C with the front end walls 25 of the openings 14 of the fixed sills A—A, and by engagement of the key E with the front end walls of the openings 15 in said fixed sills.

The combined capacity of the springs J—J 30 is preferably such that the friction shock absorbing mechanisms will be fully compressed before the former have reached their full compression.

As will be evident during the draft action 35 described, the mechanism at the other end of the car will be operated in a reverse manner to that just described. The movable draft sills B will be pulled forwardly, as hereinbefore pointed out, until the key E at that 40 end of the car has its movement limited.

In buff, the action of my improved railway draft rigging is substantially the reverse of the action in draft. Assuming that the drawbar 12, as shown at the left-hand end of Figure 2 is forced inwardly, the follower block G will be forced inwardly in unison therewith, carrying the wedge block 31 inwardly also, against the combined resistance of the friction shoes 30 and the spring L. During 45 this action, the spring elements J will yieldingly oppose relative movement of the sills B and A and, through the key which is fixed to the sills B, movement of the combined friction shell and yoke F will be yieldingly opposed, thereby effecting compression of the friction shock absorbing mechanism at the 50 same time that the spring resistance elements J are compressed. Compression of the friction shock absorbing mechanism is limited by 55 engagement of the key C with the inner end walls of the slots or openings 17 and engagement of the key D with the inner end walls of the openings 18 and 28, and relative movement of the sills B and A and compression 60 of the spring resistance elements J is arrested 65

upon engagement of the key E with the inner end walls of the openings 15 of the center sills A.

During the described buffing action, the mechanism at the other end of the car will 70 be actuated in a reverse direction, the draw sills B being pulled forwardly during the compression of the spring resistance elements J, until movement is limited by the key E at that end of the car. In case buffing forces 75 are applied simultaneously to the couplers at the opposite ends of the car inward movement of the draw-bars 12 at both ends of the car will be effected, compressing both friction shock absorbing mechanisms between the 80 keys D and E until movement of the keys D is arrested by engagement with the inner end walls of the openings 18 in the sills B, the forces thus being transmitted to the sills B 85 only.

From the preceding description, taken in connection with the drawings, it will be evident that I have provided a draft rigging for railway cars which includes shock absorbing means of high capacity and relatively great 90

movement during compression, and so arranged as to distribute the forces along the center sills of the car at spaced zones, also that the forces transmitted to the center sills all act in the same direction, thereby reducing the strain on the sills and the car body to a minimum, and preventing distortion and buckling of the parts. This is a great advantage over draft mechanisms as heretofore employed, wherein the forces act in opposite directions inwardly of the car, thus tending to place the entire structure under compression with the result that there is danger of the sills and other parts buckling or bending. It is also pointed out that in addition to the movement allowed between the continuous drawbar formed by the movable center sills and the car proper, the movement provided between the movable sills and each drawbar facilitates starting of a long 100

train of cars, inasmuch as the friction shock absorbing means of the series of cars in the train will be operated in succession, thereby permitting each car to be started in advance 105 of the next succeeding car.

While I have herein shown and described what I consider the preferred manner of carrying out the invention, the same is merely 110 illustrative, and I contemplate all changes and modifications which come within the scope of the claims appended hereto.

I claim:

1. In a draft rigging for railway cars, the combination with longitudinally extending 125 draft sills fixed to the car; of a pair of spaced sills movable with respect to the fixed sills, said spaced sills extending from end to end of the car; cushioning means opposing relative longitudinal movement of the movable 130

and fixed sills; a coupler at each end of the car; yoke means at each end of the car; a key extending through the shank of each coupler and connecting the same to the corresponding yoke means, said key extending through openings in the yoke, movable sills and fixed sills; shock absorbing means within the yoke; an outer follower cooperating with each shock absorbing means; a key extending through each follower and having its opposite ends working in openings in the yoke and movable sills, said key normally engaging the outer end walls of the openings in the movable sills; means for limiting relative movement of the fixed and movable sills; and means for resisting inward movement of each yoke with respect to the movable sills.

2. In a draft rigging for railway cars, the combination with spaced, longitudinally extending sills fixed to the car; of spaced sills extending from end to end of the car and mounted for movement lengthwise of the car with respect to said fixed sills; cushioning means opposing relative movement of the fixed and movable sills; a key fixed to the movable sills adjacent each end of the car and having its opposite ends working in guide openings in said fixed sills; a yoke at each end of the car having its movement inwardly of the movable sills limited by engagement with the last named key; a coupler at each end of the car; a key for connecting each coupler to the corresponding yoke, said coupler key having a lost motion connection with the yoke and movable sills; shock absorbing means actuated by each yoke; and an outer follower cooperating with each shock absorbing means and normally held against outward movement with respect to the movable sills.

3. In a draft rigging for railway cars, the combination with spaced, longitudinally extending sills fixed to the car; of spaced sills extending from end to end of the car and mounted for movement lengthwise of said first named sills; cushioning means opposing relative movement of said sills; a coupler at each end of the car; a yoke at each end of the car; a key connecting each yoke to the corresponding coupler for actuating the yoke in draft and having a lost motion connection with the movable sills whereby the key and coupler have limited movement outwardly and inwardly of the movable sills; a friction shock absorbing means within each yoke; follower means cooperating with each friction shock absorbing means; a key extending through the follower means and fixed thereto, said key working in openings in the movable sills and normally engaging the outer end walls of said openings to limit outward movement of the corresponding follower means with respect to the movable sills; and a key at each end of the car cooperating with the inner end of the corresponding yoke, said

last named key being fixed to the movable sills.

4. In car construction, the combination with an underframe including bolsters and laterally spaced fixed center sills secured thereto, said sills extending from end to end of the car; of a pair of laterally spaced movable sills mounted between said center sills, the movable sills extending from end to end of the car; cushioning means operatively reacting between said center and movable sills and yieldingly opposing relative longitudinal movement thereof; a coupler at each end of the movable sills and longitudinally and laterally movable with respect thereto said 70 couplers having the shank portions thereof disposed between and embraced by said movable sills; front and rear stop acting means adjacent each end of the movable sills, said stop acting means being mounted on and 75 movable with the movable sills; a cushioning device operatively interposed between each set of said front and rear stop-acting means and operable in buff and draft actions of the 80 respective adjacent coupler; and yoke-acting means operatively associated with each coupler and the adjacent cushioning device, said rear stop means at each end of the movable sills having shouldered engagement with the 85 fixed sills for limiting the movement of the 90 movable sills relative to the fixed sills in either direction.

5. In car construction, the combination with an underframe including bolsters and laterally spaced fixed center sills secured thereto, said sills being continuous from end to end of the car; of a pair of spaced movable sills mounted between said center sills, said 100 movable sills extending from end to end of the car; cushioning means reacting and operatively interposed between said center and movable sills and yieldingly opposing relative longitudinal movement thereof; a coupler at each end of the movable sills and 105 longitudinally and laterally movable with respect thereto; outer stop-acting means adjacent each end of the movable sills, said stop-acting means being mounted on and movable with the movable sills; a cushioning device operatively interposed between each set of 110 said inner and outer stop-acting means and operable in buff and draft actions of the respective adjacent coupler; yoke-acting means operatively associated with each coupler and the adjacent cushioning device; and means for limiting the movement of the movable sills relative to the center sills including connecting stop keys fixed to one pair of sills, and having lost motion connection with the other pair of sills, said keys forming inner 115 stop means for the cushioning device.

6. In car construction, the combination with an underframe including bolsters and laterally spaced fixed center sills secured thereto and extending continuously from one 120

end of the car to the other; of a pair of spaced movable sills mounted between said center sills, said movable sills extending from end to end of the car; cushioning means reacting and operatively interposed between said center and movable sills, said cushioning means being disposed inwardly of the bolsters; a coupler at each end of the movable sills and longitudinally and laterally movable with respect thereto; inner and outer stop-acting keys adjacent each end of the movable sills, said stop-acting keys being mounted on the movable sills and said inner stop-acting keys being fixed to said pair of movable sills and having lost motion connection with the fixed sills for limiting the movement of the movable sills relative to the center sills in either direction; a cushioning device operatively interposed between each set of said inner and outer stop-acting keys and operable in buff and draft actions of the respective adjacent coupler; yoke-acting means operatively associated with each cushioning device; and a key extending through each coupler, yoke, and the corresponding ends of the fixed and movable sills.

In witness that I claim the foregoing I have hereunto subscribed my name this 9th day of December, 1927.

JOHN F. O'CONNOR.
